UNITED STATES PATENT OFFICE

CHARLES E. KLAUS, OF WILKINSBURG, PENNSYLVANIA

FOUNTAIN PEN

Application filed April 25, 1928, Serial No. 272,817. Renewed June 19, 1930.

This invention relates to improvements in fountain pens, and it consists of the constructions, combinations and arrangements herein described and claimed.

5 An object of the invention is to provide an auxiliary ink reservoir for fountain pens, the contents of which may readily be discharged into a main reservoir when the latter runs dry, the necessity for drawing upon the auxiliary reservoir serving as an indication that the fountain pen requires refilling.

10 Another object of the invention is to improve the so-called self-filling fountain pen to the extent of providing main and auxiliary ink reservoirs, and a novel arrangement of pressure strips and levers by which both reservoirs may be refilled simultaneously, and the contents of the auxiliary reservoir discharged into the main reservoir, respectively.

15 Other objects and advantages appear in the following specification, reference being had to the accompanying drawings, in which

20 Figure 1 is a perspective view of a fountain pen having the improvements incorporated therein,

25 Figure 2 is a longitudinal section of one end of the fountain pen, the reservoir and the actuating assembly thereof being shown in what is herein regarded as a normal position.

30 Figure 3 is a sectional view illustrating the action of the main lever in depressing both reservoirs prior to a filling operation,

35 Figure 4 is a sectional view illustrating the action of the auxiliary lever in depressing the auxiliary reservoir for a discharge of ink into the main reservoir,

40 Figure 5 is a cross section taken on the line 5—5 of Figure 2,

Figure 6 is a perspective view of the main lever,

Figure 7 is a perspective view of the auxiliary lever,

Fig. 8 is a plan view of the main spring,

45 Figure 9 is a plan view of the main presser strip,

Figure 10 is a plan view of the auxiliary spring,

50 Figure 11 is a plan view of the auxiliary presser strip,

Figure 12 is a plan view of the actuating assembly.

The advent of the so-called self-filling fountain pen has been of undeniable advantage to frequent users of a writing implement 55 of this character. The mere requirement of inserting the point of the fountain pen into a vessel of ink for the filling of the ink reservoir by simply releasing the previously lifted filler lever has undoubtedly promoted the use 60 of the fountain pen. The obviation of the formerly known fountain pen fillers and the attendant trouble of unscrewing the pen, with the perpetual danger of soiling the fingers, clothing, etc., comprises a direct 65 contribution to the almost universal acceptance of the fountain pen.

While it may not be axiomatic that every advantage has some disadvantage, yet it is true, even in respect to self-filling fountain 70 pens, that the supply of ink becomes exhausted too soon. This difficulty often occurs at most inopportune times. One may be in the act of signing a letter, only to have the 75 pen run dry.

It appears that the solution of the difficulty lies in the provision of a reservoir from which an additional supply of ink may be drawn. Such a reservoir has been incorporated in the improved pen disclosed herein, but in addition to supplying the mere function of an auxiliary reservoir, that circumstance is herein employed as an indicator of the necessity for the refilling of the pen. In other words, when the supply of ink is so far diminished 85 that the auxiliary reservoir must be drawn upon, it is time to refill the pen.

Reference is now made to the drawing. The pen barrel 1 is of any known construction. It has a slot 2 affording communication 90 with the interior. It is within and behind the slot that a certain actuating assembly is located. That assembly controls the ink reservoirs, as presently appears.

The ink reservoirs comprise a rubber or other flexible sac 3, which differs in its construction from similar sacs, commonly used in fountain pens, by the provision of a constriction 4 which divides the sac into main 95 and auxiliary reservoirs 5 and 6. The con- 100

striction is like a small neck. Its formation is permanent, that is to say, the constriction does not disappear when the sac is distended, as is seen in Figure 2. The sac is suitably connected with the pen point.

5 The neck produces a relatively small orifice 7 in which the phenomenon of surface tension acts to retain a volume of ink in the auxiliary reservoir. It is through the orifices that ink from the auxiliary reservoir 6 is discharged into the main reservoir 5 when needed. The function of the actuating assembly may now have consideration.

10 A main presser strip 8 serves to simultaneously depress the main and auxiliary reservoirs 5 and 6 prior to filling them with ink (Fig. 3). An auxiliary presser strip 9 serves to depress the auxiliary reservoir 6 alone (Fig. 4) in order to discharge the contents 15 thereof into the main reservoir 5. The two presser strips are of stiff metal or other material. They are not supposed to bend for they are intended to press portions of the sac flat.

20 25 Separate and distinct levers are supplied for each presser strip. The main lever 10 (Fig. 6) actuates the main presser strip 8 (Fig. 3). The auxiliary lever 11 (Fig. 7) actuates the auxiliary strip 9 (Fig. 4). These levers are independently pivoted at 12 and 13. The pivoting occurs in the slot 2, and the pivot pins are held in the adjacent portions of the barrel 1 as shown in Figures 1 and 5.

30 35 The levers are nested for the sake of compactness. The pivot pin 13 of the lever 11 avoids the sides of the main lever 10 by occupying clearances 14 in the latter (Fig. 6). These clearances are formed by cutting away 40 portions of the main lever which is of channel formation. The pivot pin 12 of the lever 10 passes under the lever 11, the former having ears 15 to receive it. The main lever is bent up in a U-shape at places as indicated in 45 Figure 6. A receptacle for the lever 11 is thus provided.

50 One end of the main lever terminates in a finger nail-lift 16 by which the lever is withdrawn from the slot 2 preparatory to refilling the pen. Similarly, one end of the lever 11 terminates in a finger nail-lift 17 for the same purpose. The two nail-lifts are opposite to each other. Lifting of the lever 10 in one direction depresses both reservoirs (Fig. 55 3) while lifting of the lever 11 in the opposite direction depresses the auxiliary reservoir only.

55 Springs 18 and 19 support the respective strips 8 and 9. The parts are riveted together or otherwise secured as at 20 and 21. The springs are very thin and flexible, the main purpose thereof being to hold the presser strips in place. The two springs are bent to provide heels collectively designated 22.

60 65 The latter are secured together and to a

support 23 which is stationed at the bottom of the barrel 1. The support may be mainly in the nature of a ring to fit within the barrel. It should be designed to stay in place. It must not move within the barrel because that would result in a misalignment of the actuating assembly.

70 75 Slits 24 and 25 in the main spring 18 respectively admit the main lever 10 and auxiliary lever 11 when the latter are turned to engage the respective presser strips. The auxiliary spring 19 has a slit 26 in registration with the slit 25 so that the auxiliary lever 11 may reach the presser strip 9. The free extremity of the main presser strip 8 is forked or slotted at 27 to receive the spring 19 when the parts are in the normal position (Fig. 2), and to avoid interference with the spring when the main presser strip acts to depress both reservoirs.

80 85 It is to be noted that the breadth of the forked end of the main presser strip 8 is the same as that of the auxiliary presser strip 9. The presser strips thus overlap. The forked end thus bears against the auxiliary presser strip when the main lever 10 is actuated, thus causing both strips to function in the depression of the sac 3. In this respect the action of the presser strips is cumulative. The spring 19 is slightly narrower than the slot 27.

90 95 The operation is readily understood. Figure 2 has been assumed as illustrating a normal position of the sac 3 and the actuating assembly. The main and auxiliary levers are substantially flush with the outside surface of the pen barrel. Assume the necessity of filling the pen, that is to say the sac 3. The main lever 10 is raised to the position in Figure 3. One end of the slit 24 acts as a stop for the lever, limiting the movement to a right angular position in respect to the pen barrel. Depression of the main strip 8 and the simultaneous depression of the auxiliary strip 9 causes nearly complete compression of the main reservoir 5, and the entire auxiliary reservoir 6, driving out most of the air. A release and restoration of the lever 10 causes simultaneous filling of both the reservoirs with ink.

100 105 110 115 Assume the supply of ink in the main reservoir to have become exhausted. The ink in the auxiliary reservoir 6 will remain where it is because of the surface tension of the liquid in the orifice 7. The phenomenon is to be identified with eye droppers, ear syringes and the like. It is required to fill the main reservoir 5 from the auxiliary reservoir 6. Invert the fountain pen so that it points to the ceiling. Raise the auxiliary lever 11 so that the position in Figure 4 is assumed.

120 125 130 One end of the slit 26 in the spring 19 acts as a stop to limit the movement of the lever to a position at right angles to the pen

barrel. The depression of the auxiliary strip 9 forces the ink from the reservoir 6 into the reservoir 5. The pen is restored to the writing position. The ink in the main reservoir runs down toward the point. If the auxiliary lever 11 is now lowered, the auxiliary reservoir will expand, drawing in air from the main reservoir instead of ink.

Since the main reservoir will be only partly full of ink there is no danger of redrawing any into the auxiliary reservoir. The latter will fill with air, and other air from outside will bubble up through the ink in the main reservoir to establish an equilibrium. The pen is now ready for use, but the user must see to it that he refills the pen at the first opportunity although he now has a supply sufficient for considerable writing.

The advantages of the improvement are as follows: Embarrassment of a lack of supply of ink when the ability to write may be most insistent, is avoidable. The necessity for drawing upon the auxiliary reservoir serves as a primary warning that the pen will soon run dry. The provision of the auxiliary reservoir supplies the writer with enough ink for immediate requirements.

While the construction and arrangement of the improved fountain pen is that of a generally preferred form, obviously modifications and changes may be made without departing from the spirit of the invention or scope of the claims.

I claim:—

1. A fountain pen comprising a barrel, a flexible sac located within the barrel having a constriction dividing it into main and auxiliary reservoirs and defining a connecting orifice, a pair of overlapping pressers, and selective means for either pressing upon one presser thus to depress both pressers and collapse both reservoirs simultaneously or upon the other presser to collapse only one reservoir.

2. A fountain pen comprising a barrel, a flexible sac located within the barrel having a constriction dividing it into main and auxiliary reservoirs and defining a connecting orifice, a pair of overlapping presser strips, a lever to engage one of the strips and so move one of the strips away from the other and depress one of the reservoirs, and a second lever to engage the other strip which engages the first strip so that both move simultaneously and so depress both reservoirs.

3. A fountain pen comprising a barrel, a flexible sac located within the barrel having a constriction dividing it into main and auxiliary reservoirs and defining a connecting orifice, main and auxiliary presser strips, resilient means for individually supporting the strips in normal engagement with each other, a lever to move against the main strip and so move the auxiliary strip therewith by virtue of said engagement to depress both

prior to filling the reservoirs, and a lever to move against the auxiliary strip only to depress the auxiliary reservoir and discharge the ink content into the main reservoir.

4. A fountain pen comprising a barrel, a flexible sac in the barrel having a constriction dividing it into main and auxiliary reservoirs and defining a connecting orifice, a main presser strip disposed over the auxiliary reservoir and a part of the main reservoir, an auxiliary strip disposed over the auxiliary reservoir, resilient means individually supporting the presser strips but in normal engagement with each other, a lever to move the auxiliary strip out of said engagement for depression of the auxiliary reservoir to discharge the ink content into the main reservoir, and a lever to move against the main strip, thus to move both strips by virtue of said engagement, and depress the main and auxiliary reservoir preparatory to a filling operation.

5. A fountain pen comprising a barrel with a slot, a flexible sac in the barrel divided into connected main and auxiliary ink reservoirs, main and auxiliary presser strips, resilient means individually supporting the presser strips but in normal engagement with each other, a lever to move the auxiliary strip out of said engagement and against the auxiliary reservoir to discharge the ink content into the main reservoir, a lever to move against the main strip and so move both strips against the reservoirs by virtue of said engagement to depress the latter preparatory to filling, and pivots by which the levers are individually mounted in nested relationship in the slot.

6. A fountain pen comprising a barrel having a slot, a flexible sac in the barrel being divided into connecting main and auxiliary reservoirs, main and auxiliary levers shaped to permit nesting in the slot, pins by which the levers are pivoted for individual movement in the slot, an auxiliary presser strip which is actuated by movement of the auxiliary lever to depress the auxiliary reservoir, a main presser strip which is actuated by movement of the main lever to depress both reservoirs, a pair of springs by which the presser strips are individually supported but in normal contact with each other so that the latter function may result, and means within the barrel to support both springs and presser strips.

7. A fountain pen comprising a barrel with a slot, a flexible sac in the barrel divided into connected main and auxiliary reservoirs, main and auxiliary levers formed to permit nesting in the slot, pins by which they are pivoted in the slot for individual movement, a main spring having two slits, an auxiliary spring having a single slit in registration with one of the slits, an auxiliary presser strip carried by the auxiliary spring being actuated by the auxiliary lever through the

- registering slits to depress the auxiliary reservoir, a main presser strip with which the auxiliary strip is held in normal engagement by the auxiliary spring, being actuated by the main lever through the remaining slit to move both strips against both reservoirs, and means within the barrel to which the springs are attached thus supporting the strips.
- 10 8. An actuating assembly for a fountain pen comprising a main presser strip having a forked end, an auxiliary presser strip on which said end is superimposed, main and auxiliary springs attached to and supporting the respective strips, the spring of the auxiliary strip working in the forked end, both springs being slotted, a main lever which is movable through the slit of one of the springs to bear against the main strip, and
- 15 an auxiliary lever working through said other slits and said forked end to bear against the auxiliary strip.
9. An actuating assembly for fountain pens comprising a main lever of channel formation having ears, a finger nail-lift and cut-away portions forming clearances, an auxiliary lever nested in the main lever and having a finger nail-lift, a pivot pin received by the ears and a pivot pin passing through the auxiliary lever and being situated in said clearances.
10. A fountain pen comprising a barrel having a slot, a plurality of connected reservoirs in the barrel, and an actuating assembly located within and behind the slot comprising overlapping pressers respectively bearing on each of the reservoirs, and levers pivoted in the slot being arranged to depress the pressers singly or cumulatively.
- 15 11. A fountain pen comprising a barrel having an opening, a plurality of reservoirs in the barrel, and an actuating assembly accessible at the opening comprising pressers respectively bearing on each of the reservoirs, and means arranged to depress the pressers.
12. A fountain pen having a barrel, a flexible ink sac to supply a pen point consisting of a plurality of connected reservoirs, compressor mechanism located between the ink sac and a wall of the barrel, and selecting means mounted on said wall, being operable against said mechanism in one direction to cause compression of all of the reservoirs and in another direction to cause compression of only one reservoir.
- 15 13. A fountain pen having a barrel with an opening, a plurality of connected ink reservoirs in the barrel, compressor mechanism accessible at the opening comprising pressers for each of the respective reservoirs, and means operative in the opening to variously actuate said mechanism.
14. A fountain pen having a barrel with an opening, a plurality of connected ink reservoirs in the barrel, means movable in the

opening to cause either simultaneous compression of all of the reservoirs or compression of only one, compressor means which is acted upon by the foregoing means for carrying out said compressions, and means by which the compressor means is supported by the barrel independently of the reservoirs and of said foregoing means.

15. A fountain pen having a barrel with an opening, an ink sac in the barrel comprising a pair of connected reservoirs, compressor mechanism for acting on the sac comprising a pair of connected pressers and resilient means supported by the barrel by which one of the pressers is carried, and means operative in the opening to engage either presser respectively to simultaneously compress both reservoirs or compress only one reservoir.
